(57) **CLAIM**

The ornamental design for a front panel of a video display, as shown and described.

DESCRIPTION

FIG. 1 is a perspective view of the front panel of a video display.

FIG. 2 is a front view of the front panel of a video display of FIG. 1.

FIG. 3 is a top view of the front panel of a video display.

FIG. 4 is a bottom view of the front panel of a video display.

FIG. 5 is a right side view of the front panel of a video display; and,

FIG. 6 is a left side view of the front panel of a video display. The portions of the front panel of a video display shown in broken lines form no part of the claimed design.
